Sathrop S. Bacon of Rochester N.Y.
Letters Patent No 268. Dated Feby 26. 1850.

The schedule referred to in these Letters Patent and making part of the same.

To all whom it may concern:

Be it known that I, Sathrop S. Bacon, of the City of Rochester, county of Genesee & State of New York, have invented or produced a new design in the shape, form or configuration of a stove plate designed for the front plate of the elevated oven of a Cook Stove, and I do hereby declare that the following is a full & exact description of the same, reference being had to the accompanying drawings which make a part of this specification - In which Fig. 4. represents a perspective view of a Cook Stove with an elevated oven, Fig. 1. represents a view the Stove plate designed for the front plate of an elevated oven & its location in such oven is seen at letter A fig. 4 - Fig. 2. represents a section of said plate fig. 1. showing the shape or configuration of its surface on a line drawn from a. to b. through the centre perpendicularly. Fig. 3. represents a section of said plate fig. 1. showing the shape, form or configuration of the plate on a line drawn from c to d through the middle of the said plate horizontally.

I do not claim the figures in this plate fig. 1. as being new.

275

Ms. 168

but what I do claim as my invention & desire to secure by Letters Patent is the peculiar form, shape, or configuration of the said stove plate Fig. 1. to be used as the front oven plate to an elevated oven. Such shape form or configuration being a design independent of any particular ornaments.

Witnesses.
